UNITED STATES PATENT OFFICE

2,296,318

ELECTRICALLY FIRED BOREHOLE GUN

Robert R. Thompson, Houston, Tex., assignor to
Standard Oil Development Company, a corpora-
tion of Delaware

Application March 17, 1939, Serial No. 262,367

6 Claims. (Cl. 164—0.5)

The present invention is directed to a gun perforator for use in boreholes and has particular reference to a firing circuit therefor.

An object of the present invention is the provision of a gun perforator adapted to be fired electrically, the wiring of the firing circuit of which is arranged wholly on the exterior of the gun in a readily accessible manner.

An additional object of the present invention is the provision of a device of the character described having a firing circuit so constructed that the bullets can be fired consecutively at any desired time interval by the application of a voltage which increases linearly as distinguished from logarithmically with the number of shots, 15 whereby, for a given number of shots, a smaller voltage range will be sufficient.

Another object of the present invention is the provision of a gun perforator of the character described having a firing circuit operable on alternating or direct current and requiring only a single conductor cable in the borehole for operation.

An additional object of the present invention is the provision of a gun perforator of the character described in which the firing circuit is so arranged that the voltage applied is grounded behind each bullet in succession and this ground connection is broken upon the discharge of the bullet so as to make the voltage available for the firing of the next bullet.

Still another object of the present invention is the provision of a gun perforator of the character described in which the firing mechanism has no moving parts.

Further objects and advantages of the present invention will appear from the following detailed description of the accompanying drawings, in which—

Figure 1 is a vertical section through a borehole in diagrammatic form showing the general assembly of a gun perforator in use;

Figure 2 is a detail view of a section of the gun barrel showing the exterior arrangement of the firing circuit;

Figure 3 is a schematic illustration of the firing circuit; and

Figure 4 is a section along the line A—A of Figure 2.

Referring to the drawings in detail, numeral 1 designates a borehole provided with a casing 2, and filled with a fluid, such as drilling mud, 3. A gun barrel 4 is suspended in the borehole on a cable 5 which passes over a sheave 6 at the surface to a drum 7 mounted on suitable trun-

nions 8. The cable carries a conductor 9 which is connected through a conventional slip ring arrangement (not specifically shown), to a conductor 10 at the surface which is connected to one terminal of a battery 11, the other terminal of which is connected to a contact point 12 arranged to make periodic contact with contact members 13 mounted on a rotating switch 14, the latter being connected to a ground electrode 15 by a wire 16. It will be understood that any type switch may be employed, a simple hand switch being sufficient generally.

The gun 4 is provided with a spiral groove 17 in which is laid a wire 18 which is a continuation of conductor 9. Offset from the spiral groove in intervals are cylindrical cavities 19 fitted with plugs 20. Each plug in turn has a central bore 21 in which is fixed a bullet 22 which is insulated from the plug by a layer of insulating material 23 which may be rubber or an artificial resin. The inner end of the bullet has a circumferential flange 24 over which is fitted a rubber cap 25, secured in place by threaded ring 26. The plug 20 is recessed and threaded at its inner end to receive the flange 24, the cap 25 and the ring 26 in such a manner that when the bullet is fired the flange is sheared off by the shoulder 27 in bore 21. Plug 20 is exteriorly threaded for engagement with the body of the gun barrel. Extending inwardly from cavity 19 is a smaller cavity 28 which contains a powder can 29 in which is a filament 30, one end of which is connected to the inside of can 29, and the other end of which is connected to a contact button 31 extending through a fiber disc 32 in the outer end of can 29 and contacting the inner end of the bullet.

A branch wire 33 connects conductor 12 to the bullet. Spaced from the junction of wire 33 and wire 18 is a second junction between wire 18 and another wire 34 which is connected to an insulating post 35 carried by the outer annular face of plug 20. Arranged diametrically opposite to post 35 is a conductive post 36, and between 45 these posts is a strip 37 of conducting material so arranged as to be ruptured when the bullet discharges.

Between the two aforesaid junctions in line 12 is a resistor 38 which is generally selected to be substantially equal to the resistance of wire 33 plus the bullet, plus filament 30. The circuit, including wire 18, is grounded on the low side of resistance 38. Resistance 38 can have a higher value, but it will serve its purpose when it has the aforesaid value, and, at the same time, re-

duces the amount the voltage has to be increased in order to fire successive bullets.

The firing circuit is shown schematically in Figure 3. It will be seen that for each bullet there is a resistance 38 and a ground wire 34. The current which is transmitted through line 9 divides between branch line 33 and resistance 38. By suitably selecting the value of resistance 38 the proper amount of current to cause heating of filament 33 can be passed through line 33. When the filament becomes heated it sets off the powder contained in powder can 29 which projects the bullet from the gun. As previously stated, the bullet in discharging will rupture the ground wire 37 which may be constructed of small diameter insulated wire or with a weak point where it connects to binding post 35, so that the gap in the wire will be large compared to the diameter of the wire and will eliminate any possibility of its severed ends coming together again. It is to be noted that until the uppermost bullet is fired the applied current cannot get to the subsequent bullets, at least not in amounts sufficient to discharge them.

The firing arrangement of the present invention has been described above with reference to the use of direct current. In some respects, alternating current may be more desirable since it permits the use of a stepdown transformer in the gun itself, thus minimizing the effect of cable leakage and providing much better voltage control on the firing elements. In using alternating current the preferred embodiment is to alter the circuit shown in Fig. 3 by substituting a source of alternating current for battery 11, shifting the switch 14 to a position between the source of current and the gun, and inserting a step-down transformer in cable 9.

It will be understood that the above described specific embodiment of the present invention is submitted purely for illustrative purposes. Various changes in size, shape and arrangement of parts are contemplated within the scope of the present invention which is defined by the appended claims in which it is intended to claim this invention as broadly as the prior art permits.

I claim:

1. A perforating gun for boreholes comprising a gun body, bullets mounted for radial discharge from said gun body, a powder chamber arranged behind each bullet, a firing filament in each of said outer chambers, and a firing circuit including a source of power, a conductor connecting said source of power to each of said filaments,

5 a resistance arranged in parallel with each of said filaments, there being a separate resistance for each filament, and a conductor independent of said filaments for connecting each of said resistances separately and individually to the ground.

2. A perforating gun, according to claim 1, in which the ground connection for each resistance comprises a conductor arranged to be ruptured 10 by the discharge of the bullet.

3. A perforating gun comprising a gun barrel, a spiral groove in the surface of said barrel, a conductor laid in said groove, means for connecting said conductor to a source of power, wells arranged in said gun barrel at spaced intervals along said groove and spaced therefrom, a bullet in each of said wells, a powder chamber behind each of said bullets, a firing filament in each of said chambers, a resistance arranged in 15 said conductor adjacent each of said wells, and an electrical connection between each of said filaments and the high side of its adjacent resistance.

4. A gun perforator, according to claim 3, in 20 which a conductor is arranged across each well in such a manner as to be ruptured by the discharge of the corresponding bullet, having one of its ends connected to the gun barrel and its other end connected to the low side of the adjacent resistance.

5. A perforating gun for boreholes comprising a gun body, bullets mounted for radial discharge from said gun body, a powder chamber arranged 25 behind each bullet, an electrical firing means in each of said powder chambers, and a firing circuit, including a source of power, a conductor connecting said source of power to each of said firing means, a resistance arranged in parallel 30 with each of said firing means, there being a separate resistance for each firing means, and a conductor independent of said firing means for connecting each of said resistances to the ground 35 separately and individually.

6. In a perforating gun for bore holes provided with a well, a bullet in said well, a powder chamber behind said bullet provided with an electrical firing means, and a firing circuit connected to said firing means, in combination, a 40 resistance connected in parallel with said firing means, and an electrical conductor connecting said resistance to a ground, said conductor being arranged to be ruptured when the bullet is discharged.

ROBERT R. THOMPSON.
